CLAIM

The ornamental design for a urinal screen, as shown and described.

DESCRIPTION

FIG. 1 is a perspective view of a preferred embodiment of the urinal screen, showing my design.

FIG. 2 is a front elevational view;

FIG. 3 is a rear elevational view;

FIG. 4 is a bottom plan view;

FIG. 5 is a top plan view;

FIG. 6 is a side elevational view when viewed from the right side;

FIG. 7 is a side elevational view when viewed from the left side; and,

FIG. 8 is an exploded perspective view when viewed from the rear illustrating the rear cover removed to expose the interior of the urinal screen, the parts shown in dotted lines are not a part of the drawings.
